UNITED STATES PATENT OFFICE

JOHN C. BUCKBEE, OF CHICAGO, ILLINOIS

CONCRETE RAILROAD TIE

Application filed December 6, 1929. Serial No. 412,079.

This invention relates to improvements in railroad ties, and more particularly to ties constructed of reinforced concrete and of an improved design calculated to increase the stability of road beds and to improve operating conditions of railroads generally.

The function of ties in railway construction is too well known to require an extended discussion. In brief, the ties are embedded 10 in the road bed at relatively short intervals and the rails laid along the ties and anchored by spikes. Tie plates are usually inserted between the ties and the rails together with some form of anti-creeping device to prevent 15 the rails from shifting lengthwise.

Assuming a tie to be roughly eight feet in length and the standard gauge of track to be approximately five feet between rail centers, it follows that the rails are supported 11/2 20 feet from the ends of the ties and 2 1/2 feet from the centers. Taking into consideration the fact that the center of a road bed tends to remain compact and solid while the outer edge portions tend to loosen and become soft 25 under the action of passing trains, it follows that there exists a condition of improper load distribution, considering each tie as a beam and the road bed as the foundation, and the further fact that a tie not only supports the rails at points much nearer the 30 ends than the center, but the foundation is less solid beneath the end portions of the rails which support the greater portion of the load on the rails. The result therefore 35 is that the trackway, i. e., the ties and rails, tend to balance on the more solid central portion of the road bed unless this condition is overcome by continuous track maintenance, that is, by tamping the ballast under 40 the ends of the ties.

With the continual increase in the weight of rolling stock used upon railroads, it becomes increasingly apparent that while the size of rails has been materially increased, 45 the foundations upon which the rails are laid have not kept pace, with the result that the problem of road maintenance is one of the major concerns of railway operation. It is therefore the chief object of the present 50 invention to provide a tie which departs

from the usual design by taking into account and correcting the inequality of load distribution existent in the ordinary tie, by providing greater bearing areas at the ends lying outside of the rails.

A further object of the invention is to provide a reinforced concrete tie having ample strength to withstand the stresses to which it is subjected, and capable of resisting deterioration over a long period of years.

And finally, the object of the invention is to provide a practical and satisfactory anchorage for the rail upon the tie, with the provision for adjustment in the width of rail flange or in the gauge of the track.

A preferred embodiment of the invention is disclosed in the accompanying drawings, in which

Figure 1 is a top plan view of the tie and rail anchorage assembly;

Figure 2 is a view in side elevation of the tie with rails supported thereon;

Figure 3 is a perspective view of the tie;

Figure 4 is a view in cross section taken on line 4—4 of Figure 2;

Figure 5 is a view in end elevation of the tie;

Figure 6 is an enlarged top plan view of the rail anchorage assembly;

Figure 7 is a perspective view of the anchor plate; and

Figure 8 is an enlarged detail view in vertical section taken on line 8—8 of Figure 6.

Considering the tie as a structural member, it is in reality a reinforced concrete beam designed to meet the load conditions peculiar to its function as a support for rails. The tie would be made in a mold or form according to the usual practice in the mixing and pouring of concrete and the ingredients being selected and proportioned to give the tie the desired strength.

In its general dimensions and proportions, the tie is approximately 8 feet in length and of substantially square section throughout its central portion, although its height is slightly greater than its width. The end portions of the tie diverge or spread laterally to approximately twice the width

of the central portion, these widened end portions being outside of the rails.

Thus assuming the gauge of the rails to be approximately 5 feet, they would be supported on the tie at a distance of, say $1\frac{1}{2}$ feet inwardly from each end, and from these points the tie gradually widens along divergent lines to the full width.

Considering then the bottom supporting surface of the tie, the contour is such that the combined areas of the end portions lying outside of the rails approach or exceed the area of the central portion lying between the rails. In short, the primary purpose in the designing of the tie is to equalize the supporting values outside of the rails with that between the rails. This does not mean that the areas need be exactly equalized or that the end portions need have a tapered conformation, but rather that the end portions be substantially widened so that the load distribution will be properly spread throughout the length of the tie.

Thus, as shown in Figures 1 to 3, the tie constructed of reinforced concrete has a central portion 1 of, say, 6 inches in width and 7 or 8 inches in height. The widened end portions 2, 2 begin to widen outwardly at points inwardly from the center lines of the rails 3, 3 and just below the inside edge of the bottom flange of the rails, as shown in Figure 1, and continue to points halfway between the rails and the ends of the tie where the sides of the ties continue along parallel lines to the extreme ends.

The top of the central portion 1 of the tie is beveled or tapered slightly along its side edges for a depth of, say, 2 inches, this bevelled top section 1a being prolonged to the extreme ends of the tie.

The tie is preferably reinforced by steel rods or bars embedded in the solid concrete, and although any method of reinforcing may be employed, the following is preferred: Extending the length of the tie and lying in its central vertical plane are two straight rods 4, 4, one near the top and the other near its bottom. On either side of the center rods are two arched rods 5, 5, the central portions of these rods extending through the central portion 1 of the tie on either side of the upper straight rod 4, and thence inclined downwardly, bringing their end portions along the bottom of the end portions of the tie and in the plane of the lower straight rod 4.

For fastening the rails 3, 3, to the tie, the following parts are preferably employed: Channel-shaped tie plates 6, 6, seat upon the tie in inverted position beneath the rails, their side flanges fitting snugly over the beveled top section 1a thereof, thus securely holding it against transverse displacement or in a direction lengthwise of the rails.

If desired, cushions or pads 6a of oiled felt or other materials may be inserted between the top of the tie and the plates to aid in absorbing the shock of passing trains and to give a better bearing of the tie plate on the tie.

Embedded in the tie just beneath the tie plates 6, 6 are anchor plates 8, 8 consisting of hollow metal castings of a general U-shape, with their top faces lying flush with the top face of the tie. As shown in Figure 7, each casting has two parallel hollow arms 7a, 7a, having pairs of T-slots 7b, 7b extending longitudinally from opposite sides of rectangular openings 7c, 7c disposed centrally of the arms. These arms are connected integrally at one end by a tapered housing 8 having a rectangular opening 8a in its top surface near its apex. This opening is elongated slightly in a direction transversely of the casting, and extending inwardly therefrom and in line with its end edges are a pair of upright parallel walls 8b, 8b within the housing forming a cavity below and inwardly beyond the opening. Also integral with the anchor plate and depending from the central portion of each of the arms 7a, 7a thereof are cylindric anchors 9, each having an enlargement 9a at its lower end and axial passages 9b communicating with the interior of the hollow arms 7a at their upper ends. As shown in Figure 8, these anchors are of sufficient length to extend downwardly through the tie with their lower ends flush with the bottom surface thereof, the vertical passages serving to permit the drainage of any water that may accumulate in the hollow spaces in the casting above.

As shown in Figure 8, the anchor plates 7 are covered by the tie plates 6 with the exception of the tapered end portions 8, which project beyond the outer end of each tie plate, with the rectangular openings 8a exposed. Drilled through each tie plate are pairs of bolt holes 6b, 6b, one pair on each side of the rails and just beyond the edges of the bottom flange thereof. Moreover, these bolt holes register with the T-slots 7b, 7b in the anchor plate 7 beneath. Thus before the rails are laid, four rail bolts 10 are fitted into each anchor plate by inserting their head ends into the large central opening 7c in each arm 7a and then sliding them outwardly to the ends of the T-slots. The threaded ends of the bolts are then inserted through the bolt holes in the tie plates 6 as the same are fitted onto the tie, and then after the rail has been laid in place, clips 11 are mounted on the projecting ends of the bolts overlapping the bottom flange of the rail and nuts 12, 12 lastly applied and tightened down.

To complete the rail anchorage a rail brace is preferably added to the assembly,

the same being applicable to either one or both rails, to each tie or to ties at various intervals apart, depending on the requirements at any given point along the road bed. The brace is designed to serve both as a support on the outside of a rail and as an adjusting member to permit lateral shifting of the rail.

The rail brace consists of a cast metal shoe 13, having a head 13a shaped to fit snugly against the side of the rail between the head and the bottom flange and a tapered extension 13b projecting laterally beyond the edge of the bottom flange of the rail and bearing upon the tie plate 6. The shoe 13 has a backing member 14 consisting of a block of metal having a curved or hook-shaped projection 14a at its lower end adapted to be inserted through the opening 8a in the extended end portion 8 of the anchor plate, with its end projecting laterally into the cavity below said opening. The main portion of the block projects above the anchor plate and along its outer face is an integral lug 14b which seats upon the outer edge of the anchor plate and thus holds the backing block against displacement. Mounted in the backing block is a set screw 15 extending horizontally therethrough and turning in a nut 16 which seats in a recess 16a formed in the inner face of the block. The end of the set screw bears against a vertical abutment face at the outer end of the shoe 13, while its opposite end extends beyond the outer face of the block and is provided with a square head 15a, and adjacent thereto is a check nut 17.

The rail brace may be omitted as a part of the rail anchorage, in fact, the anchor plate 7 may be designed without provision for receiving the backing block 14 and thus serve only as retainers for the rail bolts. However, to avoid the necessity of providing more than one type of tie, it is preferred to use the same anchor plate for all ties and omit the rail brace where not needed.

It may be explained in connection with the anchor plate that provision for drainage is considered desirable in view of the possibility of water accumulating and freezing in the hollow interior sections, with the possibility of rupturing the casting.

And finally, it is to be noted that a continuous V-shaped groove 18 extends entirely around the sides and ends of the tie, midway between the top and bottom. The purpose of this groove is to permit the use of tongs or other mechanical equipment for handling and laying the ties.

Having disclosed a preferred embodiment of my invention, I claim:

1. A railroad tie comprising a beam of reinforced concrete having a relatively narrow top section extending throughout its length, inverted channel-shaped tie plates

seating over said top section at the points of rail support, anchor plates embedded in said tie beneath said tie plates, each comprising a hollow casting provided in its top wall with slots extending transversely beyond the edges of the rail flange and having enlarged entrance openings beneath said tie plates, rail bolts adapted to have their head ends inserted into said slots and to project upwardly through holes drilled in said tie plates, and rail fastening members applied to said rail bolts.

2. A reinforced concrete railroad tie comprising a beam adapted to support the rails at points inwardly from each end and having a relatively narrow top section with beveled sides extending the length of the tie, tie plates seating over said top section at the points of rail support, and rail anchoring members embedded in the top face of the tie beneath said tie plates, and comprising hollow castings having integral tubular extensions through said tie.

3. A railroad tie comprising a concrete beam adapted to support the rails at points spaced inwardly from the ends thereof, anchor plates embedded in the top surface of said beam beneath the points of rail support, and each consisting of a hollow casting provided in its top wall with an opening lying beneath the rail flange, slots extending laterally from said opening beyond the edges of said rail flange and a separate opening adjacent one edge of said rail, rail bolts adapted to be inserted into said slots and a rail brace including a block having a portion insertable in said last mentioned opening.

Signed at Chicago, Ill., this 3rd day of December, 1929.
